CHARLES LEIB.
By William Webster.

ATTORNEY.

UNITED STATES PATENT OFFICE.

CHARLES LEIB, OF PHILADELPHIA, PENNSYLVANIA.

DESIGN FOR AN EYE.

SPECIFICATION forming part of Design No. 33,949, dated January 22, 1901.

Application filed December 21, 1900. Serial No. 40,698. Term of patent 14 years.

To all whom it may concern:

Be it known that I, CHARLES LEIB, a citizen of the United States, residing at Philadelphia, in the county of Philadelphia and State of Pennsylvania, have invented and produced a new and original Design for an Eye of the Class Hook and Eye, of which the following is a specification, reference being had to the drawings forming part thereof.

- 10 In the drawings, Figure 1 is a plan view of an eye of the class known to the trade as "hook and eye," and my invention pertains to the new and useful design for an eye, as herein shown. Fig. 2 is a side view.
- 15 The leading or material features of my design comprise an eye formed of a single piece of wire in which is the central portion 1, from which the two portions of wire are bent at

right angles, whereby there is formed a rectangular body portion comprising part 1 and side parts 2 2, the strands of wire diverging from the parts 2 2 to form side bars 3 3, with the ends of the side bars 3 3 coiled to form loops 4 4, the whole forming an eye of novel construction and pleasing effect.

Having described my invention, what I claim as new, and desire to secure by Letters Patent, is—

The design for an eye of the class hook and eye as herein shown and described.

In testimony whereof I affix my signature in presence of two witnesses.

CHARLES LEIB.

Witnesses:

WILLIAM WEBSTER,
ALBERT L. TAYLOR.
